UNITED STATES PATENT OFFICE.

LESTER R. WELLMAN, OF CHICAGO, ILLINOIS, ASSIGNOR TO FRIEDELEY-VOSHARDT CO., OF CHICAGO, ILLINOIS, A CORPORATION OF ILLINOIS.

DESIGN FOR A LANTERN.

Application filed March 24, 1925. Serial No. 12,866. Term of patent 7 years.

To all whom it may concern:

Be it known that I, LESTER R. WELLMAN, part thereof being shown, it being understood that the remainder is identical in construction, in the county of Cook and State of Illinois, have invented a new, original, and ornamental Design for a Lantern, of which the following is a specification, reference being had to the accompanying drawing, forming part thereof.

Fig. 1 is a side elevation showing my new design.

Fig. 2 is a fragmentary plan view, only part thereof being shown, it being understood that the remainder is identical in construction.

I claim:

The ornamental design for a lantern, as

LESTER R. WELLMAN.
